(57) **CLAIM**

The ornamental design for a wastegate base, as shown and
described.

DESCRIPTION

FIG. 1 is a top, front left perspective view of a wastegate
base shown according to the present design;

FIG. 2 is a bottom, rear left perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is front end view thereof;

FIG. 8 is a rear end view thereof;

FIG. 9 is a cross-sectional view thereof taken along line 9-9
in FIG. 1; and,

FIG. 10 is a cross-sectional view thereof taken along line
10-10 in FIG. 1.

1 Claim, 5 Drawing Sheets
